UNITED STATES PATENT OFFICE.

EMMA WORCESTER DOUGHTY, OF RAMAPO, NEW YORK, ASSIGNOR TO CHENEY BROTHERS, OF SOUTH MANCHESTER, CONNECTICUT, A CORPORATION OF CONNECTICUT.

DESIGN FOR A TEXTILE FABRIC.

No. 38,100.

Specification for Design.

Patented June 19, 1906.

Application filed May 15, 1906. Serial No. 317,008. Term of patent 3½ years.

To all whom it may concern:

Be it known that I, EMMA WORCESTER DOUGHTY, a citizen of the United States, residing at Ramapo, in the county of Rockland and State of New York, have invented a new, original, and ornamental Design for Textile Fabrics, of which the following is a specification, reference being had to the accompanying drawing, forming a part thereof.

The figure is a plan view of the fabric, showing my new design.

I claim—

The ornamental design for a textile fabric, as shown.

EMMA WORCESTER DOUGHTY.
